UNITED STATES PATENT OFFICE.

ALBERT S. BIERLY, OF CHICAGO, ILLINOIS.

PROPELLSIVE-SPRING FOOT SUPPORT.

Application filed July 14, 1924. Serial No. 725,846.

My invention relates to a spring foot support and particularly to a spring support for the foot which is of assistance in locomotion. It has for one object to provide a cushion adaptable for use either with or without a skate. Another object is the provision of a foot support which shall automatically, in response to pressure of the foot, tend to throw or catapult the user forward on the rebound. Another object is the provision of a cheap and simple toy. Other objects will appear from time to time in the course of the specification and claims.

I illustrate my invention more or less diagrammatically in the accompanying drawings, wherein—

Figure 1 is a view of my invention as applied to the foot when used without a skate;

Figures 2 and 3 are similar views of various forms of my invention; and

Figure 4 illustrates the application of one form of my invention to a skate.

Like parts are indicated by like characters throughout the specification and drawings.

In the form shown in Figure 1 A is the sole of the shoe. B and C are the spring engaging and ground engaging arms respectively of a unit spring member, the two arms being connected, for example, by the bent portion D. D¹ is any suitable resilient support, herein shown as a block or pad of resilient material, such as rubber. With this form of my invention, the downward pressure of the foot depresses the upper foot engaging element B toward the ground engaging element C, thus bending the member D and compressing the resilient element D¹. When the pressure of the foot is released, the other foot being placed upon the ground, the combined action of the bent portion D and the resilient member D¹ moves the element B upwardly, and in a general sense, rotates it about the point adjacent the bend D. Since the rear end of the member distends from the center and describes a relatively long arc, the rebound has a tendency to throw the user, not only upwardly, but forwardly along its path.

In the form shown in Figure 2, the elements B and C are separate and are hinged as at E. E¹ is a resilient member corresponding to D¹, but herein shown as a spiral spring. In order to supply the place of the resiliency of the bend D of the one piece, I provide the rear spiral spring E² herein

shown as secured to the element B and terminating short of the element C, although, of course, it might be secured to both. In order to limit the upward movement of the element B in response to the action of the spring E¹ or E², I provide a limiting guard E⁴ secured both to the upper element B and the lower element C. The action of the form of Figure 2 is the same as that of Figure 1 and there is the same tendency to throw the foot and body forwardly as well as upwardly. The spring E² substitutes for the connecting bend D of the form of Figure 1, both in adding to the resiliency of the whole member and in taking part of the strain which would otherwise fall upon the element E¹.

In the form shown in Figure 3, the elements B and C are connected by the relatively stiff spiral spring G. The opposed yielding elements G¹ and G² limit the downward movement of the element B and add to the resiliency of the device. G⁴ is a limiting chain or guard similar to E⁴.

In the form shown in Figure 4 the shoe A is supported on the relatively resilient shoe engaging element H, which in turn is supported upon the ground engaging tread plate H¹. H and H¹ are connected at their forward ends by the semi-circular leaf spring J and at their rear ends by a similar, but stronger semi-circular leaf spring J¹. Interposed between the elements H and H¹ are a plurality of spiral springs K, K¹ and K² all secured at their upper ends to the member H. At the rear the member H also normally engages the member K, it being longer than the springs K¹ and K² and being put under compression sooner, exerts a more powerful thrust. When the type of the invention shown in Figure 4 is used, it has the same tendency as the other three to throw the foot forwardly as well as upwardly. It may also be used with a skate of any other type. To illustrate this I have shown in Figure 4 in dotted lines a skate with caterpillar tread, having a plurality of supporting rollers or cylinders L, and a tractor belt M. It will be understood that this skate is represented as an illustration and not as a limitation to be used with the particular type of skate shown.

While I have illustrated an operative device, it will be realized that many changes might be made in the size, shape, number and disposition of parts without departing

from the spirit of my invention, and I wish my description and drawings, to be taken as in a broad sense diagrammatic and illustrative.

6 The use and operation of my invention are as follows:

A yielding pad or support between foot and skate is frequently desirable to lessen the shock of the skate and to make a more 10 comfortable, and, as it were, easy riding skate, particularly where the skate is of the caterpillar type, and is used over relatively rough surfaces. I therefore provide a yielding member which may be interposed between 15 the foot and the skate, when it is used with skates. This member is not merely a cushion, however, but is so constructed as to tend to lift the foot higher at the rear than at the front of the skate, when the weight of 20 the foot is withdrawn, thus employing yielding members or springs interposed between foot and skate to make the forward movement of the user easier, and to catapult him forward. As one foot is put down and weight 25 on the other foot is relaxed, the intermediate yielding member acts more powerfully on the rear of the foot and tilts the body forward and tends to throw the user forward.

The same principle may be employed 30 where no skate is used, and is particularly adapted to the manufacture of a toy for children, a species of elastic pattern. In its simplest form it consists simply of a shoe 35 engaging foot plate or tread plate, and a ground engaging lower plate, and a resilient connection between them which operates to lift the rear of the foot plate higher than the forward end. It will be understood that 40 any of the forms herein shown might be applied to a skate, although they are illustrated as detached therefrom. When these sim-

ple catapults are used, the foot is preferably spaced back from the pivot or forward end of the catapult, as shown in Figure 1.

I claim:—

1. In a yielding propulsive support, a generally flat relatively extended ground engaging member, a foot supporting member in rotatable relation with the forward end thereof, and yielding means interposed between said foot engaging member and said ground engaging member adapted to rotate the rear end of the foot engaging member a substantial distance above said ground engaging member. 45

2. In a yielding propulsive support, a generally flat relatively extended ground engaging member, a foot supporting member in rotatable relation with the forward end thereof, and yielding means compressed between 50 said foot engaging member and said ground engaging member, adjacent their point of attachment, adapted to rotate the rear end of the foot engaging member a substantial distance above said ground engaging member. 55

3. In a yielding propulsive support, a generally flat relatively extended ground engaging member, a foot supporting member in rotatable relation with the forward end 60 thereof, and yielding means interposed between said foot engaging member and said ground engaging member adapted to rotate the rear end of the foot engaging member a substantial distance above said ground engaging member. 65

Signed at Chicago, county of Cook and 70 State of Illinois, this 2nd day of July, 1924.

ALBERT S. BIERLY.
